TORQUE WRENCH OR THE LIKE

Karl-Heinz Müller, Wuppertal-Cronenberg, Germany, assignor to Belzer-Werk R. Belzer, Wuppertal-Cronenberg, Germany, a corporation of Germany

Filed July 23, 1968, Ser. No. 12,861

Claims priority, application Germany Jan. 23, 1968

Term of patent 14 years

Int. Cl. D8—02

U.S. Cl. D8—24

FIG. 1.

FIGURE 1 is a front elevation of a torque wrench or the like, showing my new design;

FIG. 2 is a top plan view of the same at an enlarged scale and fragmented for ease of illustration;

FIG. 3 is a bottom plan view of the same at an enlarged scale and fragmented for ease of illustration;

FIG. 4 is a front elevation of the same at an enlarged scale fragmented for ease of illustration and with the head in section for completeness of disclosure;

FIG. 5 is one end view thereof; and

FIG. 6 is another end view thereof.

I claim:

The ornamental design of a torque wrench or the like, as shown and described.
